Dennis L. Rogers
ATTORNEY.

UNITED STATES PATENT OFFICE.

JOHN H. FRY, OF GRAND RAPIDS, MICHIGAN, ASSIGNOR OF ONE-HALF TO
EDGAR A. FLETCHER, OF SAME PLACE.

ADJUSTABLE FOLDING DESK.

SPECIFICATION forming part of Letters Patent No. 450,580, dated April 14, 1891.

Application filed February 24, 1891. Serial No. 382,653. (No model.)

To all whom it may concern:

Be it known that I, JOHN H. FRY, a citizen of the United States, residing at Grand Rapids, in the county of Kent and State of Michigan, have invented certain new and useful Improvements in Adjustable Folding Desks; and I do hereby declare the following to be a full, clear, and exact description of the invention, such as will enable others skilled in the art to which it appertains to make and use the same.

My invention relates to improvements in adjustable folding desks. My object is to provide a means of adjusting the vertical inclination of the desk-top and arresting such inclination at any desired angle, as well as to provide a simple and effective means of adjusting the other coacting parts and stiffening and strengthening the structure; and it consists in the construction, combination, and arrangement of the various parts hereinafter described, and particularly pointed out in the claims, reference being had to the accompanying drawings, wherein—

Figure 1 represents a transverse vertical section of a device embodying my invention, on the line *y y* of Fig. 3, open, with the top adjusted at a slight angle; Fig. 2, the same folded; Fig. 3, a longitudinal vertical section on the line *y y* of Fig. 1; Fig. 4, a detail of detached portion.

Like letters indicate like parts throughout the drawings.

A represent the two leaves or oppositely-inclined sides of the top. They are hinged upon opposite sides to opposite side edges of the horizontal bar *D*, which has a strip *E* secured upon its upper side between the inner edges of said leaves, upon which is detachably placed the cap-strip *F*, provided with pins *L*, engaging suitable apertures or sockets therein. The bar *D* has at each end vertically-arranged depending bars *C*, having slots *C'* in the lower portion thereof, and provided with angle-braces *II* for rigidity and strength. The cross-legs *B* are hinged oppositely to opposite leaves *A* at their upper ends, and the opposite pairs are connected together by a clamping-rod *H*, upon the outer ends whereof the pairs are respectively pivoted, and which is provided with washers *N* and thumb-

nuts *M* and arranged within the tubular spreading-bar *G*, the outer ends whereof engage the inner sides of the bars *C* for limiting the inward movement of both the bars *C* and legs *B*, and thereby giving rigidity to the structure, and the projecting ends of the rod *H* pass through slots *C'* in bars *C*, and thence through the cross-legs, and its tension is adjusted at either end by thumb-nuts *M*, whereby, as is obvious, the bars *C* may be vertically adjusted, and thereby the opening and closing of said cross-legs and the inclination of the leaves *A* is provided for. At the lower edge of the leaf *A* is arranged a strip *J*, provided with a retaining-screw *K*, arranged in diagonal slot *O*, whereby said strip may be adjusted as desired to prevent articles from sliding off.

What I claim as new, and desire to secure by Letters Patent of the United States, is—

1. The combination of horizontal bar *D*, leaves *A*, hinged at its side edges, depending bars *C*, clamping-rod *H*, engaging the bars *C* and provided with nuts *M*, and cross-legs *B*, hinged to leaves *A* and pivoted on rod *H*, substantially as and for the purposes set forth.

2. The combination of horizontal bar *D*, leaves *A*, hinged at its side edges, depending bars *C*, having slots *C'*, clamping-bar *H*, engaging slots *C'* and provided with nuts *M*, and cross-legs *B*, pivoted on rod *H*, and hinged to leaves *A*, substantially as set forth.

3. The combination of horizontal bar *D*, leaves *A*, hinged at its side edges, strip *E*, secured on the bar *D* and between the edges of leaves *A*, as set forth, depending bars *C*, having slots *C'*, clamping-bar *H*, engaging slots *C'* and having nuts *M*, and cross-legs *B*, pivoted on rod *H* and hinged to leaves *A*, substantially as set forth.

4. The combination of horizontal bar *D*, leaves *A*, hinged at its side edges, depending bars *C*, clamping-rod *H*, engaging the bars *C* and arranged within the tubular spreading-bar *G*, the spreading-bar *G*, and cross-legs *B*, pivoted on rod *H* and hinged to leaves *A*, substantially as and for the purposes set forth.

5. The combination, with the horizontal bar *D*, having the leaves *A* hinged upon each side thereof, and the strip *E*, attached to bar *D* and arranged between the leaves *A*, as set

forth, of the cap-strip F, arranged upon the strip E, substantially as set forth.

6. The combination, with the leaf A, of the strip J, having diagonal slot O, and screw K, 5 arranged within the slot, as set forth.

7. The combination, with the horizontal bar D, having leaves A hinged at its side edges, and the strip E, arranged thereon and between the edges of said leaves, depending bars 10 C, having slots C', crossed legs B, hinged to leaves A, clamping-bar H, engaging slots C' and having nuts M, and spreading-bar G, arranged below the bar D and engaging the inner sides of the bars C, substantially as and 15 for the purposes set forth.

8. The combination, with the horizontal bar

D, having leaves A hinged at its side edges, and the strip E arranged thereon and between the edges of said leaves, depending bars C, having slots C', braces I, crossed legs B, 20 hinged to leaves A, clamping-bar H, having nuts M and arranged within spreading-brace G, and engaging the slots C', and the spreading-brace G, arranged between bars C, substantially as described, and for the purposes 25 herein set forth.

In testimony whereof I affix my signature in presence of two witnesses.

JOHN H. FRY.
